UNITED STATES PATENT OFFICE.

CHARLES GILBERT HAWLEY, OF CHICAGO, ILLINOIS.

STEAM BOILER AND SETTING.

Application filed September 12, 1921. Serial No. 500,107.

My invention relates to improvements in steam boilers, including the settings and furnaces therefor.

This application is a continuation of certain of the subject matters disclosed and claimed in my former case S. N. 304307, filed June 14, 1919, allowed March 18, 1921, and abandoned in favor of this application.

The object of the invention is to provide a boiler of a new type, for heating and power purposes; and which, compared with those now in use, shall be of less weight, of smaller size, of lower cost, and less expensive to install and to maintain;—and especially, to provide a boiler which shall be safer and more durable than others;—particularly under conditions of forced firing. A special object of the invention is to provide a boiler that shall be better adapted to a more rapid circulation of the boiler water and the efficient utilization of the radiant heat of the fire, and therefore of greater capacity and efficiency. Further special objects are to provide a boiler of a unit form, complete in itself, and to the end that either a single boiler or a plurality thereof may be used in a single setting or fire chamber, and to the further end that the novel boiler, in each of several standard sizes, may become a standard factory product adapted, for manufacture by economical quantity production methods, and in sizes best suited to such processes of manufacture, and for transportation by rail or water.

I attain these objects and other objects hereinafter set forth by novel arrangements of heating surfaces, and by novel constructions throughout the boiler and the boiler setting; all as hereinafter described and particularly pointed out in the appended claims.

The invention will be readily understood on reference to the accompanying drawings, wherein I have illustrated the invention in what I regard as its best forms, and in which; Fig. 1 is a longitudinal vertical section of a steam boiler and setting embodying my invention; Fig. 2 is a horizontal section on the line 2—2 of Fig. 1; Fig. 3 illustrates a modified form of my invention; Fig. 4 shows a further modification thereof; Fig. 5 is a vertical cross-section on the lines 5—5 of Figs. 1 and 2; Fig. 6 is a vertical cross section on the lines 6—6 of Figs. 1 and 2. Fig. 7 shows two of my novel unit boilers in a single setting; Fig. 8 is a like view show-

ing three of the units over a single grate; Fig. 9 illustrates a modified form of the forward end of the water steaming and circulating wall; Fig. 10 is a partial elevation of the top front of a three unit boiler showing how the boiler units are supported; Fig. 11 illustrates a boiler unit of larger proportions; Fig. 12 is an end elevation thereof; Fig. 13 is a vertical section on the line 13—13 of Fig. 11; Fig. 14 is a front end elevation of a unit which embodies top and bottom drums of still larger dimensions and which has two of the water steaming and circulating walls; Fig. 15 is a vertical section on the line 15—15 of Fig. 14; and Fig. 16 is a horizontal section of a water circulating wall, as viewed on any of the lines 16—16 of the several figures.

I may build my unit boilers, assemblies thereof, and the settings therefor, in many different sizes and shapes to suit various conditions, and it is to be understood that the structures herein shown and described are by way of illustration only, and are not to be regarded as the limits of the invention. Thus, all of the boiler units or unit boilers, shown in Figs. 1 to 10, are of a single size; this in order to clearly present the method which I follow in multiplying the number of separate boilers or units as required to gain the desired capacity and efficiency from the boiler as a whole. In each case the dimensions of the grate may be regarded the criterion controlling the over-all dimensions of the boiler, and the number of units employed has to do with the ultimate efficiency of the boiler.

The bare boiler, or single unit, detailed in Figs. 1, 2, 5 and 6 comprises a long top drum, A, for water and steam,—a short bottom drum, B, for water and mud,—a thin, stay-bolted water-wall, C, of generally triangular shape, leading from the drum B into the bottom of the drum, A—and a group of vertical water tubes, or other return passage, D, joining the bottom of the drum A, and the top of the drum B. In this form, the unit or boiler is ready for installation, and is fitted for actual use by adding the necessary safety valve, water gauge, feed-water and blow-off connections. When two or more units are used in a single setting, the bottom drums are interconnected, as by couplings G (Figs. 7 and 8) to ensure a uniform water level in the top drums, and the several steam outlets, H, of the units are

joined, as by the steam pipe or drum I, to equalize the steam pressure therein.

Attention is called to the arrangement of the tubes D and the complementary parts 5 on the upper and lower drums. The tube sheet portion of the upper drum, that is, the lower portion of that drum at the rear end, comprises a separate sheet; likewise the tube sheet portion of the lower drum comprises 10 a separate sheet; thus, the tubes and tube sheets may be assembled as a separate shop unit and the structure is not complete until both component tube sheets have been incorporated with the drums to which they 15 belong.

The circulation of water is from the bottom drum, B, upward through the water wall, C, thence freely into the bottom of the top drum, A, thence rearwardly in the 20 drum A, and thence downward through the return tubes, D, thus accomplishing the return to the bottom drum, B. As shown the tubes and the drum B are positioned in a rearward extension 3 of the fire chamber 1. 25 This portion 3 will be referred to as the gas passage which contains the water tubes. It is made into a tortuous passage by means of the several baffle walls F. As shown, in each case, the water wall, C, is positioned in the 30 fire chamber 1 where it receives the intense radiant heat of the flames from the grate 2, hence the described circulation is very rapid; ensuring high capacity, and internal cleanliness. The mud or sediment accumulates 35 in the bottom of the drum, B, from whence occasionally it is discharged through a blow-off pipe J and valve J'. The boiler may receive the feed water through the connection K.

40 The part, L, (Figs. 1 and 6) is a steam collector leading to the outlet H.

The part M (Figs. 1 and 5) is a long, perforated plate occupying a horizontal position midway of the upper drum A. This 45 plate is of a width which allows it to be introduced, and withdrawn, through the man-hole A' at either end of the drum. The circulation of the water in this boiler is extremely rapid, and the rise of water through 50 the water wall, C, is so vigorous as to make some such baffle, as the plate M, desirable as a means to prevent the priming of the steam at the outlet H. The part N (Figs. 1 and 55 6) is a similar plate, which may be inserted and withdrawn through the man-hole B' in the bottom drum. This plate need not be perforated. Its function is to serve as a baffle for the downward moving streams from the tubes D, and thus to prevent any 60 such agitation in the bottom of the drum, B, as would dislodge or disturb the mud and sediment which accumulates there.

As indicated by the feathered arrows in Fig. 1, the gases from the fire pass between 65 the many water tubes, D, before reaching

the stack or exhaust passage, E, whatever the position of the latter. Enough tubes, D, are used to ensure the absorption of the heat from the non-flaming gases and hence to insure a low stack temperature. This action 70 may be furthered by the use of many different arrangements of baffle walls in and about the group of tubes, D; such as the various baffles, F, shown in different parts of the drawings. Whatever the form and arrangement of the baffles, it will be found that the tubes D, and the bottom drum or drums provide convenient and substantial supports therefor.

Sometimes, notably under high-rate-of- 80 combustion conditions, the drums should be lengthened and the number of the tubes increased to ensure an efficiently low stack temperature.

As to both capacity and efficiency, chief 85 reliance rests upon the described free and rapid circulation, and, the very effective radiant-heat absorbing surfaces presented by the water-wall, C, and the underside of the top drum, to which may be added the 90 first one or two rows of tubes, D. Essentially, this is a radiant heat boiler. Being such, it is of high thermal efficiency and generally is of about half the size, half the weight, and half the cost of present-day 95 boilers of the same capacity.

Each unit is a complete boiler and may be so used up to its capacity, as limited by the combustion in its firebox. See Figs. 5 and 6. Beyond this, a boiler of any desired 100 total capacity may be secured by placing a number of the units side by side within a single fire-chamber as shown in Figs. 7 and 8. Large capacities and high efficiencies are thus attainable with boiler units of 105 relatively small size and weight.

These units are adapted for economical quantity production by the best modern methods. And as the complete unit (in either one or two sections) is of comparatively 110 small size, it is easy to transport and erect in its completed form; and, in particular, is most economical in the matter of shipment upon commonly available railway cars, trucks and boats.

115 As before stated, these units may be made in several different sizes and shapes, but in any case all problems of manufacture are greatly simplified, the process consisting in the mere multiplication of a given standard unit or units best suited, singly and collectively, to meet all demands upon the manufacturer and users.

Each boiler (unit) of the proportions shown in Figs. 1 to 10 so to speak is made 125 in one piece, and is transported in that form. The larger units, such as I have illustrated in Figs. 11 to 14, for convenience of manufacture and shipment is made in two sections. One section comprises the water 130

wall C^x , the drum head B^x , and the front half A^x of the top drum. The other section comprises the back half A^y of the top drum, the bottom drum B^y and the many 5 watertubes D^x , which join the drums. Each section is completed at the factory. On arrival at the place of installation the sections are telescoped (as indicated by dotted and full lines in Fig. 11) and they are then 10 riveted together, as shown at points O in Fig. 11. The joints are then caulked or welded to make them steam tight. Thus the work in the field is reduced to a minimum.

For the further study of the practical 15 phases of the matter, it may be assumed that the exemplary boiler unit shown in Fig. 1-8 is fourteen to eighteen feet long and little over nine feet high; that the two drums, A and B , and the water-wall, C , 20 are made of sheets three-eighths of an inch thick; that the water space, (Fig. 5) in the water-wall is three to four inches wide; that the drums A and B are about twenty-four inches in diameter; and, that the tubes 25 D , are of twelve gauge and two-and-a-half inch diameter. A unit of such dimensions weighs about five thousand pounds, and when used singly in a setting, such as shown in Figs. 5 and 6, is of one hundred to one 30 hundred and fifty horse power capacity, within the range of ordinary rates of combustion in the fire chamber.

As a further example, the large power 35 unit of Figs. 11 and 12 may have the following dimensions. Each section has a length of about ten feet, which adapts them for shipment on ordinary railroad cars. The drums are of thirty two inch diameter. The water space within the wall C^x may be 40 from three to four inches wide. The capacity of such a unit ranges from one hundred and fifty to two hundred and fifty boiler horse-power, according to the rate at which it is fired.

Desired increases of capacity may be 45 secured by placing two or more of these units in a single setting and such multiplication of units may well be resorted to for the purpose of providing a boiler of maximum efficiency.

I now call attention to the varying shapes 50 of the water circulating and steaming walls shown in Figs. 1, 3, 5, 9 and 11. While of different shapes each thereof is of an inverted substantially triangular shape; inasmuch as each presents a neck shaped apex C^y to the bottom drum, and presents a wide base C^w to the top drum. As well shown the area of the "neck" or intake connection 55 C^y in every case, is very much smaller than the outlet opening or slot C^u , within the base portion C^w . The water which enters 60 from the bottom at high velocity, so to speak, takes on or expands to the shape of a fan within the thin water wall, and rapidly

ascends therein due to much of it being evaporated, but always moves at a much lower speed than at the intake C^y . It is in the sense of this paragraph that I shall hereinafter employ the term "substantially triangular" water wall. As a rule also, this implies that the true bottom or lower part C^r of the water wall trends or slants upward from the intake, so that the spreading or fanning out of the water may take place without so great a cessation of upward movement as to admit of the deposition and accumulation of mud or loose scale in the forward part of the water wall. As a further precaution in this last respect I equip 75 some of these water walls with means C^z for blowing off any accumulations that may be found therein.

Each water wall is made preferably of one sheet of metal folded upon itself and with its meeting edges flanged together and welded as shown in Fig. 16. The flat sides of the wall are then joined by properly spaced stay bolts S . Where the wall is of large size I obtain the single sheet, in effect 80 by welding or riveting together the necessary number of smaller sheets or parts. With the assistance of autogenous welding it is an easy matter to obtain, from sheet steel or sheet copper, any of the shapes shown in 85 the drawings.

The water wall of Fig. 1 is of a single triangular form. This form is departed from in Fig. 9, with a view to increasing the heating surface. But in this last regard I 100 much prefer the structurally simpler shape shown in Figs. 3 and 11. There the wall is distinguished by a distinct blow-off neck C^s ; and beside, has the advantage of a bulging bottom, or beam, portion C^t which is of 105 uniform diameter from neck C^y to neck C^s . In passing, it should be explained that these bulging bottom portions are distinctly advantageous because they ensure the free and uniform distribution of the strong currents 110 of water that enter through the intake neck C^y , and furthermore, as they are self stayed it becomes unnecessary to carry the stay bolting so low as to obstruct the flow of water or mud upward along the bottom of 115 the water wall.

That modification shown in Figs. 14 and 15 seems to be self explanatory. Thereby, I succeed in doubling the water wall capacity, in proportion to the drum and water tube portions of the unit. To do this, I employ a main top drum C^2 (for the water tubes) and provide each water wall C^3 with its own top drum C^4 . These are smaller, so that two thereof may enter and be attached to the front head C^5 of the main drum C^2 .

The parts A^w which appear in Figs. 11 and 13 are applicable to, and typify my boilers in their most desirable form. They 120

are likewise applicable to any steam boiler which comprises drums and water tubes which occasionally must be cleaned. In my boilers all of the internal surfaces are accessible through the man holes provided in the ends thereof. But I much prefer the addition of the parts A^w. They are small hand-holes, with covers, and are spaced at convenient distances in or upon the top of the boiler. Through these a man working in an upright position upon the top of the boiler may easily insert and work the usual cleaning tools, as indicated by the flexible shaft, power driven de-scaling tool P, shown in Fig. 13. Those who are familiar with the ordinary difficulties of washing and cleaning steam boilers will at once understand the convenience and importance of this simple improvement.

20 Keeping in mind the proportions or dimensions above assumed, and referring to the single, dual and triple unit boilers shown in Figs. 1, 2, 5, 7 and 8 it will be found that, as illustrated, the proportionate grate area of the single unit boiler is twenty-eight square feet; of the dual unit boiler thirty six square feet; and of the triple unit boiler fifty square feet. I have utilized these proportions to further exemplify the ease with 25 which the capacity may be ensured by using a grate area of any desired size and also to show how a boiler of any reasonably high efficiency (boiler and furnace efficiency) may be secured by multiplying the number of units while lessening the proportionate grate area; and yet always securing required capacities in boilers of comparatively small size, weight and cost.

Further referring to the assembly views, it 40 will be noted that the boiler units are suspended within their settings, being supported at the ends of the upper drums. Not only does this facilitate erection, but what is more important, the whole lower 45 part of the boiler unit is permitted entire freedom of expansion and contraction in all directions; and by reason of this freedom and the manner in which the bottom drum is connected to the upper drum by the parts, 50 C and D, and C^x and D^x, the effects of expansion and contraction are so minimized and distributed as to obviate possibility of rupture in any of the parts or connections.

Obviously, this boiler is safe and durable; 55 for, as indicated, the drums are of comparatively small diameter; the metal sheets composing the drums and the water-walls, though actually thin, are relatively heavy; the effects of expansion and contraction are 60 nullified; ample feed water capacity or temporary storage is provided in the bottom drum, likewise ample space for mud in the coolest part of the boiler; complete provision is made for the free disengagement of steam 65 rising into the upper drum, and provisions

are made for keeping the boiler clean and free from scale; each of which points has an important bearing upon the safety and durability of the boiler.

I have herein referred to the water leg or 70 wall, C, as a thermic siphon. It acts as such, for it draws water from the lower part of the boiler and delivers steam and water to the upper part thereof. Aside from the other parts of the boiler, it closely resembles 75 the device from which it takes its names, to-wit; the Nicholson thermic siphon as used in locomotive boiler fireboxes.

As stated before, the complete unit, by 80 preference, is always suspended in its setting. As the best means to that end, I employ two saddle beams or cradles, 4 and 5, at the ends of the top drum and support these by columns 6. These columns are preferably footed in concrete below the floor 85 line of the boiler room, as indicated by dotted lines. For a single unit, each beam contains a single saddle or notch. For a plurality of units, each beam contains as many saddles as there are units (see Fig. 10). 90 Heavier beams and columns are used for the wider settings. The spacing between the saddles in such beams is determined by the dimensions of the grate and fire chamber to be used. Ordinarily, the spacing between 95 centers exceeds the drum diameter by several inches, leaving a reasonably wide crack to be closed by protecting key brick, 7. It is to be noted that the described separation of the units from one another and from the side 100 walls of the setting, is always such that a workman may enter the spaces between the water walls, as may be required.

As best shown in Fig. 1, the saddle beams, 4 and 5, preferably are Z-shaped in cross-section, and each presents a wide seat, which receives the curved bearing strip, 8, conforming to the drum. The top of each strip, 8, contains a groove that accommodates the heads of the rivets belonging to the drum head. Thus the rivet heads serve to lock the bearing strips to respective ends of the drum; and the strips form slide bearings on the saddles and at the same time tightly close the cracks between the saddles and the 110 drum. By preference the bearing strip at the rear end of the boiler is fastened to the saddle beam, whereas the bearing strip at the forward end of the drum is free to slide in the cradle of the beam, 17, and to thus 115 accommodate the longitudinal expansion and contraction of the boiler unit. For sake of stability, each pair of cross braces is braced and tied together by two rods or bars, 9, preferably positioned below the center of the top drum. In this manner a simple and complete metal support or sling is first provided for the unit or units and thereafter the setting is completed by the addition of the side and end walls, 10. It 120 125

is not necessary to burden these walls by the weight of the boiler unit or units.

As herein shown, wide spaces are left between the side walls of the setting and the 5 top drums of the boiler units. These spaces are closed by a novel roof-arrangement comprising, at each side, a plurality of slanting firebrick slabs, 11, of varying lengths as determined by the different spaces to be closed.

- 10 These slabs rest upon the tops of respective side walls, and at their upper ends lean against the adjacent boiler drum, being pitched at an angle of substantially forty-five degrees, in which position they are firm 75 and stable. The bars, 9, are removed at the time the brick are put in place or removed. The removal thereof gives access to the tubes within the gas passages of the setting. There is also a back door, 12, for that purpose. Upon the completion of the roof, the 15 entire top of the boiler is covered with a layer of suitable insulating material.

As indicated, the fire chambers, 1, may and should contain suitably positioned fire 20 arches or baffles, F', for the proper elongation of the flame travel. At this point it is well to understand that my boilers are primarily intended for use with high volatile fuels, the best results being gained when 25 the firebox is virtually filled with flames from the fire. Under such conditions the water walls are very effective as absorbers of heat, as well as ideal water circulating and steam disengaging devices.

- 30 The practical use and operation of the boiler will be obvious to all those skilled in the art. Its structural advantages have already been described and referred to, but its operation and some further advantages may 35 be properly summarized at this point. For this purpose the boiler is assumed to be in operation, containing a proper level of water constantly added to through the feed water supply pipe, with steam at given pressure 40 discharging from the outlet, H, and with a proper fire in the fire-chamber. The high temperature flames impart their heat to the directly opposed surfaces of the water walls C and to the underside of the top drum or 45 drums, A. This immediate transference of radiant heat is of prime importance. The siphon being subjected to high temperature on both sides and throughout large areas, the water therein is caused to flow forward 50 and upward in a very rapid and vigorous manner. The steam liberated on the inner surfaces of the fire sheets is therefore instantly swept from the sheets and, as will be apparent, all steam bubbles liberated within 55 the siphon rise freely and directly into the upper drum through the fan-like enlargement of the siphon in the direction of the drum. The size of the long, slot-like outlet 60 or top of the siphon greatly exceeds the size 65 of the intake neck, through which the water

enters from the drum, B, and because of this and the restriction of the thickness of the flat column of water in the wall, the movement of steam and water therein is limited to upward movement; and thus conflicting currents in 70 the siphon are avoided. The small volume of water contained in the boiler ensures the quick steaming of the water and an immediate response of the boiler to every demand for steam. In this connection it should be 75 noted that the amply long and very large outlet of the siphon into the upper drum results in the entirely free liberation and distribution of steam in the larger surfaced body of water in the upper drum and even 80 in case of a sudden and abnormal steam demand there can be no localization of steam flow into or within the upper drum and in consequence the steam therein is not primed and there is little, if any, tendency toward a 85 geyser-like action of water in the direction of the steam outlet. The steam entering the top drum from the siphon finds ample surface therein for its free and quiet disengagement, assuring a constant supply of dry 90 steam and only the hot water flows toward the rear end of the drum. All water discharged and evaporated within the hollow wall C is, of course, replaced by water flowing into it from the lower drum, B, and simultaneously, and in a positive manner, the water from the upper drum is drawn, or falls 95 downward through the many tubes, D, and into the lower drum. The movement of the water in the return tubes is slower by reason 100 of the greater aggregate area of the tubes, as compared with the neck of the siphon, and does not militate against the ready upward escape of the steam generated in the tubes by the heat to which the tubes are subjected 105 in the gas passage 3. By reason of the fact that the wall C takes water from the upper part of the bottom drum, the hot water descending through the return tubes and baffled by the plate N, tends to move directly toward 110 the siphon intake and leaves the cold feed water and the mud in the bottom thereof in a more or less quiescent state. The cold feed water therefor, reaches the siphon only after 115 its temperature has been considerably raised. The lower drum for these reasons is valuable 120 as a settling chamber or mud drum, serving as a mud trap which retains the greater part of the solids and prevents the passage thereof into the siphon and upper parts of the boiler. By occasionally blowing out the lower drum (which is done by opening the blow-off valve) the entire system can be kept 125 clean, and in consequence of this cleanliness and the absence of any surface or pocket wherein steam can collect, the boiler may be operated efficiently at overloads and over long periods. Whenever it is necessary to obtain access to the interior of the boiler, as 130 for purposes of inspecting or washing it, the

man-holes may be opened and at such times every part of the interior of the boiler becomes accessible. As explained, it is possible to wash and descale every part of the boiler including its return tubes. The specially important factor is that the most rapid, vigorous and unrestrained circulation takes place in that part or parts of the boiler subjected to the most intense heat, to-wit, in the water wall or siphon, with the result that those parts are constantly maintained in the best possible working order.

Though a boiler of great capacity may be required, following the described system it will be composed of a number of unit boilers each characterized by a drum of relatively small diameter. An important incident of the construction is that these small drums may be made of relatively thin sheets and yet be capable of withstanding high pressures. Further, such sheets can be handled, formed and shaped much more quickly, with less skill and more cheaply than the heavy plates ordinarily used in boiler construction. Again, the thin sheets more readily transmit heat, with a consequent proportional increase in efficiency.

As will be apparent, my invention is adapted to all ordinary uses of boilers in stationary, marine and portable service.

The objects and purposes outlined in the opening of the specification are attainable by the construction and arrangement herein shown and described, but inasmuch as this disclosure will suggest to others modified constructions whereby the substantial objects and purposes of my invention may be attained, I do not wish to be limited to the construction herein shown and described, except to the extent that the invention is defined in the appended claims.

Having thus described my invention, I claim as new and desire to secure by Letters Patent:—

1. A boiler unit comprising a top drum, in combination with a bottom drum, many return ducts connecting the said drums, a substantially and operatively triangular water wall occupying vertical planes parallel with the axis of said top drum communicating directly with both drums and constituting an upflow passage of increasing size from bottom to top, a fire-chamber containing said wall, and a gas passage containing said bottom drum and said return flow ducts.

2. A boiler unit comprising a long top drum, in combination with a short bottom drum beneath the rear part of the top drum and in substantially parallel relation thereto, a plurality of vertical return tubes connecting said drums, and a substantially and operatively triangular water wall which pre-

sents its apex in communication with the forward part of said bottom drum and its inverted base in communication with the forward part of said top drum.

3. A boiler unit comprising, in combination, substantially parallel top and bottom drums, the lower drum being of approximately half the length of the upper drum, a thermic siphon extending upward from the front end of the lower drum and entering the bottom of the upper drum, a group of return tubes rising from the top of the bottom drum and entering the bottom of the upper drum, the upper drum having a steam outlet, said bottom drum having a blow-off connection, and the ends of said drums containing access openings.

4. A steam boiler comprising a bank of water tubes and upper and lower drums or receivers that are carried by said tubes, in combination with a water circulating and steaming wall of inverted substantially and operatively triangular shape, which at the top opens into the bottom of said upper receiver and which at its bottom rear corner forms an intake neck in communication with said lower receiver.

5. A steam boiler comprising a bank of water tubes and upper and lower drums or receivers, in combination with a water circulating and steaming wall of inverted substantially and operatively triangular shape, which at the top opens into said upper receiver and at its bottom rear corner forms an intake neck in communication with said lower drum and said bottom presenting an upper forward corner, below said upper drum.

6. The herein described water circulating and steaming wall which has flat spaced apart and staybolted sides and is of inverted substantially and operatively triangular shape, open at the top and having an upwardly and forwardly slanting bottom which at its front, bottom portion has a blow-off neck and at its lower back end has an intake neck.

7. A boiler unit comprising a thermic siphon member, in combination with reversely positioned tube sheets and a plurality of tubes connecting them, a top sheet which with the top of said siphon member and one of said tube sheets completes the body of the upper drum, a bottom sheet which with the other tube sheet completes the body of the bottom drum, heads closing the ends of said drums and the front head of the bottom drum containing the intake portion of said siphon member.

In testimony whereof, I have hereunto set my hand this 8th day of September, 1921.

CHARLES GILBERT HAWLEY.
